FURNACE WALL

Tracy H. Sherman, South Nyack, N. Y., assignor
to Foster Wheeler Corporation, New York, N. Y.,
a corporation of New York

Application March 29, 1947, Serial No. 738,125

14 Claims. (Cl. 110—1)

1

This invention relates to furnaces and more particularly to furnace walls.

The present invention provides a furnace wall structure in which the refractory elements thereof are so supported that there is a minimum of torsional stress on said refractory elements and the wall is readily constructed without the necessity of cutting, fitting or otherwise shaping said elements during the erection of the furnace. The supporting structure requires but a minimum of metallic structure per foot of wall.

This invention further provides a wall comprising a plurality of adjacent sections in which the sections are locked in relationship to one another so as to prevent overturning of the wall.

The present invention also provides a furnace wall construction for use with furnaces having extremely high temperatures, the supporting structure of said wall being protected against intense heat and adequately air-cooled.

This invention further provides a furnace wall using standard elements and having a minimum of specially shaped parts which wall is easily and readily repaired. The wall of the present invention may be constructed to a desired thickness without changing the shape of said specially shaped parts. The width of the specially shaped parts are independent of the width of the wall.

The invention will be understood from the following description when considered in connection with the accompanying drawing forming a part thereof, and in which:

Fig. 1 is a horizontal sectional view of a portion of the furnace wall of the present invention;

Fig. 2 is a vertical sectional view taken on the line 2—2 of Fig. 1 but on an enlarged scale, and

Fig. 3 is a horizontal sectional view taken on the line 3—3 of Fig. 2.

Like characters of reference refer to like parts throughout the several views.

Referring to the drawing, Fig. 1, the reference numeral 10 designates a furnace chamber surrounded by furnace walls. As shown, a portion of the end wall is designated by the reference numeral 11, while a portion of a side wall is designated by the reference numeral 12. The end wall opposite end wall 11 and the side wall opposite side wall 12 are not shown but would be constructed in the manner similar to the walls 11 and 12, as hereinafter described.

The walls 11 and 12 comprise a plurality of horizontally spaced, vertically extending I-shaped girders or buckstays 13. The girders 13 normally extend from the top to the bottom of the wall and have secured thereto by welding or other means

at vertically spaced points along their length, right-angular shaped metallic supports 14 the vertically spaced supports of each of the girders being in the same horizontal plane as the supports on the other girders. One leg 15 of support 14 is secured to the inner leg 16 of the girders 13, while the other leg 15' of member 14 extends inwardly toward the furnace chamber. Leg 15' of members 14 have an upper surface 17 and a lower surface 18. An angle bar 19, which extends longitudinally of the wall throughout its length, is supported by the members 14 in the same horizontal plane on the various girders, said angle bar having an upwardly extending leg 20 and a leg 21 which extends inwardly toward the furnace chamber at right angles to the leg 20. Angle bar 19 is secured to the various members 14 on buckstays 13 by welding or any other desired means so that the surface 22 of the leg 21 abuts the surface 17 of the legs 15' of members 14.

The buckstays 13, members 14 and angle bar 19 provide a supporting structure for the tile or refractory elements of the wall of the present invention. The refractory elements consist of an upper refractory element 23 having an upper flat surface 24 and a longitudinally extending slot 25 adapted to receive the leg 20 of angle bar 19 in the bottom surface of said element. The bottom of element 23 has a downwardly projecting portion 26 (Fig. 2) which engages the upper surface 21 of angle bar 19 and is of substantially the same width as said leg. The element 23 has an inwardly extending portion 27 at the inner side of portion 26 and also an outer portion 27', the portions 27 and 27' being at opposite sides of the downwardly projecting portion 26. A lower refractory element 28 is positioned beneath the element 23 and is substantially L-shaped having a vertically extending leg 29 which projects upwardly to a point closely adjacent the portion 27 of element 23. Element 28 has a horizontally extending leg 30 with an upper surface 31 which normally is in spaced relationship with under surface 18 of members 14 so as to permit expansion of the portion of the wall below members 14 toward said member. The surface 31 of element 28 has apertures 32 therein adapted to receive pins 33 which are welded or otherwise secured to leg 20 of angle bar 19 at longitudinally spaced points. The element 28 rests upon a plurality of lower tiles 34 which are placed one on top of the other, the lowermost of which tiles rest upon the refractory element 23 which is supported by another angle bar 19 which in turn is supported by members 14 secured to buckstays 13 in a hori-

zontal plane lower than the horizontal plane of the first-mentioned angle bar 19. It will be noted that since downwardly projecting portion 26 of element 23 rests upon the upper surface of leg 21 of the angle bar 19 the lower surface of outer portion 27' is held in spaced relationship with surface 17 of member 14 thereby forming an air space 35 which extends longitudinally of the walls so that circulation of air adjacent the angle bar 19 and members 14 is permitted thereby cooling the supporting members of the wall.

The walls are bounded on the outer side thereof by a metallic casing 36 and a layer of insulating material 37 is provided between the casing 36 and tiles 34. Air setting cement 38 is applied between adjacent surfaces of the tiles and also between the adjacent vertically extending surfaces of leg 29 and portion 26 of said elements respectively so that adjacent tiles will be secured together thereby forming unitary wall sections. Between the upper surface of leg 29 and the adjacent surface of portion 27 of refractory elements 28 and 23 respectively asbestos fiber packing 39 is inserted so that said space will be filled and at the same time expansion of the lower wall section will be permitted.

In constructing the furnace wall of the present invention, the angle members 14 are welded to the inner leg 16 of girders 13, said angle members being secured at vertically spaced points along each of the girders with angle members of adjacent members in the same horizontal plane. The angle bar 19 is then placed so that it is supported by the leg 15' of members 14 in spaced relationship with casing 36 inwardly toward the furnace chamber, the under surface 22 of the leg 21 of angle bar 19 abutting upper surface 17 of leg 16 of the members 14. The angle bar is then attached to said members by welding or any other desirable means. Refractory element 23 is placed in position so that downwardly projecting portion 26 thereof rests upon upper surface 21 of angle bar 19 and upwardly extending leg 28 extends into slot 25 in element 23. Tiles 34 are then stacked on element 23 upwardly to a point short of under surface 18 of leg 16 of a member 14 in the horizontal plane next above the horizontal plane of first-mentioned member 14. Refractory element 28 is placed to rest upon the uppermost tile 34 and so that upper surface 31 of said tile is in spaced relationship with under surface 18 of last-mentioned member 14 so that there is space for expansion of the wall section. Other wall sections are constructed by repeating the above described operation, each of said sections being supported by angle bars 19 extending in spaced horizontal planes which bars are supported by a plurality of members 14 secured to beams 13.

Since changes may be effected in the form of the invention selected for disclosure without departing from the principles thereof, it will be understood that the invention is not to be limited excepting by the scope of the appended claims.

What is claimed is:

1. In a furnace wall comprising a lining of heat insulating material having outer and inner surfaces, exterior supporting means comprising a plurality of horizontally spaced vertically extending buckstays adjacent the outer surface of said lining, means for supporting the lining by the exterior supporting means comprising an angle

bar extending in a substantially horizontal plane, the angle bar having a substantially vertically extending leg and a substantially horizontally extending leg and being so positioned in relationship to the lining that said vertical leg extends in a vertical plane intermediate said inner and outer surfaces of the lining, and inverted L-shaped bracket supports for the angle bar associated with the buckstays and said bar, the brackets and buckstays being of substantially equal width, the angle bar being positioned on one leg of the brackets so that said plane in which the vertical leg of the angle bar extends is also intermediate the buckstays and the innermost edge of said brackets.

2. In a furnace wall comprising a lining of heat insulating material having outer and inner surfaces, exterior supporting means comprising a plurality of horizontally spaced vertically extending buckstays adjacent the outer surface of said lining, means for supporting the lining by the exterior supporting means comprising an angle bar extending in a substantially horizontal plane, the angle bar having a substantially vertically extending leg and a substantially horizontally extending leg and being so positioned in relationship to the lining that said vertical leg extends in a vertical plane intermediate said inner and outer surfaces of the lining, and inverted L-shaped bracket supports for the angle bar, said brackets being of substantially the same width as the buckstays and comprising members extending in planes substantially at a right angle to one another, one of said members being secured to a buckstay and the other member being secured to the horizontally extending leg of the angle bar, the support and the angle bar being so positioned in relationship to one another that said horizontally extending leg rests upon and is supported by said other member and the vertically extending leg projects upwardly intermediate the innermost and outermost edges of said other member of the bracket.

3. A furnace wall comprising a lining with an inner and outer surface, said lining being of refractory bricks, exterior supporting means adjacent the outer surface, means for supporting the lining by the exterior supporting means comprising an angle bar extending in a substantially horizontal plane and supported by the exterior supporting means, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, a base brick engaging said horizontally extending leg inwardly of said vertically extending leg from a point adjoining the vertical leg, said base brick extending in spaced relationship with the plane of the horizontal leg outwardly of said vertical leg to said outer surface to thereby form a longitudinally extending space adjacent said vertical leg on the side thereof toward the outer side of the lining, and a plurality of spaced pins secured to said vertically extending leg and projecting downwardly into the lining.

4. A furnace wall comprising a lining of re-

refractory bricks, said lining having an inner and outer surface and being in sections, the sections having an upper longitudinally extending edge and a lower longitudinally extending edge, exterior supporting means adjacent the outer surface, a plurality of supports extending in vertically spaced substantially horizontally extending parallel planes, each of said supports comprising an angle bar extending in a substantially horizontal plane and supported by the exterior supporting means, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, a longitudinally extending row of base bricks forming the lower longitudinal edge of a section, the base bricks engaging said horizontally extending leg inwardly of said vertically extending leg from a point adjoining the vertical leg, said base bricks extending in spaced relationship with the plane of the horizontal leg outwardly of said vertical leg to said outer surface to thereby form a longitudinally extending space adjacent said vertical leg on the side thereof toward the outer side of the lining, the upper longitudinal edge of said section of the lining being formed of a longitudinally extending row of refractory bricks closely adjacent the horizontally extending leg of the support next above said one support, and a plurality of spaced pins secured to said vertically extending leg and projecting downwardly into said bricks of the upper longitudinal edge of a section.

5. A furnace wall comprising a lining of refractory bricks, said lining having an inner and outer surface and being in sections, the sections having an upper longitudinally extending edge and a lower longitudinally extending edge, exterior supporting means adjacent the outer surface comprising a plurality of horizontally spaced vertically extending buckstays adjacent the outer surface of said lining, a plurality of supports extending in vertically spaced substantially horizontally extending parallel planes, each of said supports comprising an angle bar extending in a substantially horizontal plane, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, supports for the angle bars comprising members extending in planes substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, a longitudinally extending row of base bricks forming the lower longitudinal edge of a section, the base bricks engaging said horizontally extending leg inwardly of said vertical leg, said base bricks extending in spaced relationship with the plane of the horizontal leg outwardly of said vertical leg to said outer surface to thereby form a longitudinally extending space adjacent said vertical leg on the side thereof toward the outer side of the lining, the upper longitudinal edge of said section of the lining being formed of a longitudinally extending row of refractory bricks closely adjacent the horizontally extending leg of the support next above said one support, a plurality of spaced pins secured to said vertically extending leg and projecting downwardly into the lining, and a metallic casing along the outer side of said lining.

7. A furnace wall having a lining with outer and inner surfaces, the lining comprising a plurality of sections with an upper longitudinally extending edge and a lower longitudinally extending edge, said sections being of heat insulating material, exterior supporting means adjacent the outer surface, a plurality of supports extending in vertically spaced substantially horizontally extending parallel planes, each of said supports

horizontally extending leg inwardly of said vertically extending leg from a point adjoining the vertical leg, said base bricks extending in spaced relationship with the plane of the horizontal leg outwardly of said vertical leg to said outer surface to thereby form a longitudinally extending space adjacent said vertical leg on the side thereof toward the outer side of the lining, the upper longitudinal edge of said section of the lining being formed of a longitudinally extending row of refractory bricks closely adjacent the horizontally extending leg of the support next above said one support, and a plurality of spaced pins secured to said vertically extending leg and projecting downwardly into the lining.

6. A furnace wall comprising a lining of refractory bricks, said lining having an inner and outer surface and being in sections, the sections having an upper longitudinally extending edge and a lower longitudinally extending edge, exterior supporting means adjacent the outer surface comprising a plurality of horizontally spaced vertically extending buckstays adjacent the outer surface of said lining, a plurality of supports extending in vertically spaced substantially horizontally extending parallel planes, each of said supports comprising an angle bar extending in a substantially horizontal plane, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, supports for the angle bars comprising members extending in planes substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, a longitudinally extending row of base bricks forming the lower longitudinal edge of a section, the base bricks engaging said horizontally extending leg inwardly of said vertical leg, said base bricks extending in spaced relationship with the plane of the horizontal leg outwardly of said vertical leg to said outer surface to thereby form a longitudinally extending space adjacent said vertical leg on the side thereof toward the outer side of the lining, the upper longitudinal edge of said section of the lining being formed of a longitudinally extending row of refractory bricks closely adjacent the horizontally extending leg of the support next above said one support, a plurality of spaced pins secured to said vertically extending leg and projecting downwardly into the lining, and a metallic casing along the outer side of said lining.

7. A furnace wall having a lining with outer and inner surfaces, the lining comprising a plurality of sections with an upper longitudinally extending edge and a lower longitudinally extending edge, said sections being of heat insulating material, exterior supporting means adjacent the outer surface, a plurality of supports extending in vertically spaced substantially horizontally extending parallel planes, each of said supports

comprising a member extending in a substantially horizontal plane and supported by the exterior supporting means, each of said members having another member associated therewith and projecting in a substantially vertical plane at a point intermediate said outer and inner surfaces of the lining, said lower longitudinal edge of a section engaging one of the first-mentioned members and having a recess therein positioned to receive the other member of said support, the upper longitudinal edge of a section of the lining extending closely adjacent the support next above said one support, and a plurality of longitudinally spaced pins associated with said supports and projecting downwardly therefrom into the lining.

8. A furnace wall having a lining with outer and inner surfaces, the lining comprising a plurality of sections with an upper longitudinally extending edge and a lower longitudinally extending edge, said sections being of heat insulating material, exterior supporting means adjacent the outer surface, a plurality of supports extending in vertically spaced substantially horizontally extending parallel planes, each of said supports comprising a member extending in a substantially horizontal plane and supported by the exterior supporting means, each of said members, having another member associated therewith and projecting in a substantially vertical plane at a point intermediate said outer and inner surfaces of the lining, said lower longitudinal edge of a section engaging one of the first-mentioned members and having a recess therein positioned to receive the other member of said supports, the upper longitudinal edge of a section of the lining extending closely adjacent the support next above said one support, at least one of the longitudinal edges of a section having a longitudinal projection inwardly of said horizontal member of the supports and extending in a general vertical direction a distance to overlap said horizontal member and the adjacent longitudinal edge of an adjoining section, and a plurality of longitudinally spaced pins associated with said supports and projecting downwardly therefrom into the lining.

9. A furnace wall having a lining with outer and inner surfaces, the lining comprising a plurality of sections with an upper longitudinally extending edge and a lower longitudinally extending edge, said sections being of heat insulating material, exterior supporting means adjacent the outer surface, a plurality of supports extending in vertically spaced substantially horizontally extending parallel planes, each of said supports comprising a member extending in a substantially horizontal plane and supported by the exterior supporting means, each of said members having another member associated therewith and projecting in a substantially vertical plane at a point intermediate said outer and inner surfaces of the lining, said lower longitudinal edge of a section engaging one of the first-mentioned members inwardly of the other member associated therewith and extending to a point adjoining said other member but short of engagement with said one of the first-mentioned members outwardly of said other member to thereby form a longitudinally extending space adjacent said other member along the outer side of the lining, the upper longitudinal edge of said section of the lining extending closely adjacent the support next above said one support at least one of the longitudinal edges of a section having a longitudinal projection inwardly of said horizontal member of the supports and extending in a general vertical direction a

distance to overlap said horizontal member and the adjacent longitudinal edge of an adjoining section, and a plurality of longitudinally spaced pins associated with said supports and projecting downwardly therefrom into the lining.

10. A furnace wall comprising a lining of refractory bricks, said lining having an inner and outer surface and being in sections, the sections having an upper longitudinally extending edge and a lower longitudinally extending edge, exterior supporting means adjacent the outer surface, a plurality of supports extending in vertically spaced substantially horizontally extending parallel planes, each of said supports comprising a member extending in a substantially horizontal plane and supported by the exterior supporting means, each of said members having another member associated therewith and projecting in a substantially vertical plane at a point intermediate said outer and inner surfaces of the lining, a longitudinally extending row of base bricks forming the lower longitudinal edge of a section, the base bricks engaging one of the first-mentioned members inwardly of the other member associated therewith and extending to a point adjoining said other member but short of engagement with said one of the first-mentioned members outwardly of said other member to thereby form a longitudinally extending space adjacent said other member along the outer side of the lining, the upper longitudinal edge of said section of the lining being formed of a longitudinally extending row of refractory bricks closely adjacent the support next above said one support, the base bricks and the bricks of said upper longitudinal edge extending inwardly a distance greater than the horizontally extending member of said supports, the base bricks having a longitudinally extending inverted L-shaped recess along the innermost edge thereof and the bricks of said upper edge having a longitudinal projection extending upwardly and into the L-shaped recess of the base bricks of an adjoining section, and a plurality of longitudinally spaced pins secured to said supports and extending downwardly into the bricks of the upper longitudinal edge of a section.

11. A furnace wall comprising a lining with an inner and outer surface, said lining being of refractory bricks, exterior supporting means adjacent the outer surface, means for supporting the lining by the exterior supporting means comprising an angle bar extending in a substantially horizontal plane and supported by the exterior supporting means, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in a relationship to the lining that said vertical leg extends in a vertical plane intermediate said inner and outer surfaces of the lining, a base brick engaging said horizontally extending leg inwardly of said vertically extending leg from a point adjoining the vertical leg, said base brick extending in spaced relationship with the plane of the horizontal leg outwardly of said vertical leg to said outer surface to thereby form a longitudinally extending space adjacent said vertical leg on the side thereof toward the outer side of the lining, and a plurality of projections longitudinally spaced from one an-

other on said angle bar and extending downwardly into the lining.

12. A furnace wall comprising a lining of refractory bricks, said lining having an inner and outer surface and being in sections, the sections having an upper longitudinally extending edge and a lower longitudinally extending edge, exterior supporting means adjacent the outer surface comprising a plurality of horizontally spaced vertically extending buckstays adjacent the outer surface of said lining, a plurality of supports extending in vertically spaced substantially horizontally extending parallel planes, each of said supports comprising an angle bar extending in a substantially horizontal plane, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, supports for the angle bars comprising members extending in planes substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, and a longitudinally extending row of base bricks forming the lower longitudinal edge of a section, the base bricks engaging said horizontally extending leg inwardly of said vertically extending leg and from a point adjoining the vertical leg, said base bricks extending in spaced relationship with the plane of the horizontal leg outwardly of said vertical leg to said outer surface to thereby form a longitudinally extending space adjacent said vertical leg on the side thereof toward the outer side of the lining, the upper longitudinal edge of said section of the lining being formed of a longitudinally extending row of refractory bricks closely adjacent the horizontally extending leg of the support next above said one support.

13. A furnace wall comprising a lining of refractory bricks, said lining having an inner and outer surface and being in sections, the sections having an upper longitudinally extending edge and a lower longitudinally extending edge, exterior supporting means adjacent the outer surface comprising a plurality of horizontally spaced vertically extending buckstays adjacent the outer surface of said lining, a plurality of supports extending in vertically spaced substantially horizontally extending parallel planes, each of said supports comprising an angle bar extending in a substantially horizontal plane, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, supports for the angle bars comprising members extending in planes substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, a longitudinally extending row of base bricks forming the lower longitudinal edge of a section, the base bricks engaging said horizontally extending leg inwardly of said vertically extending leg from a point adjoining the vertical leg, said base bricks extending in spaced relationship with the plane of the horizontal leg outwardly of said vertical leg to said outer surface to thereby form a longitudinally extending space adjacent said vertical leg along the outer side of the lining, the upper longitudinal edge of said section of the lining being formed of a longitudinally extending row of refractory bricks closely adjacent the hori-

substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, and a longitudinally extending row of base bricks forming the lower longitudinal edge of a section, the base bricks engaging said horizontally extending leg inwardly of said vertically extending leg from a point adjoining the vertical leg, said base bricks extending in spaced relationship with the plane of the horizontal leg outwardly of said vertical leg to said outer surface to thereby form a longitudinally extending space adjacent said vertical leg along the outer side of the lining, the upper longitudinal edge of said section of the lining being formed of a longitudinally extending row of refractory bricks closely adjacent the horizontally extending leg of the support next above said one support at least one of the longitudinal edges of a section having a longitudinal projection inwardly of said horizontal member of the supports and extending in a general vertical direction a distance to overlap said horizontal member and the adjacent longitudinal edge of an adjoining section.

14. A furnace wall comprising a lining of refractory bricks, said lining having an inner and outer surface and being in sections, the sections having an upper longitudinally extending edge and a lower longitudinally extending edge, exterior supporting means adjacent the outer surface comprising a plurality of horizontally spaced vertically extending buckstays adjacent the outer surface of said lining, a plurality of supports extending in vertically spaced substantially horizontally extending parallel planes, each of said supports comprising an angle bar extending in a substantially horizontal plane, the angle bar having a substantially vertically extending leg and a substantially horizontally extending leg, the horizontally extending leg projecting inwardly of said exterior supporting means, the vertically extending leg being disposed intermediate the inner end of the horizontally extending leg and the inner side of said exterior supporting means, the angle bar being so positioned in relationship to the lining that said vertical leg extends in a vertical plane intermediate said inner and outer surfaces of the lining, supports for the angle bars comprising members extending in planes substantially at a right angle to one another, one of said members being secured to a buckstay and the other member being secured to the horizontally extending leg of the angle bar, the supports and the angle bars being so positioned in relationship to one another that said horizontally extending leg rests upon and is supported by said other member, a longitudinally extending row of base bricks forming the lower longitudinal edge of a section, the base bricks engaging said horizontally extending leg inwardly of said vertically extending leg from a point adjoining the vertical leg, said base bricks extending in spaced relationship with the plane of the horizontal leg outwardly of said vertical leg to said outer surface to thereby form a longitudinally extending space adjacent said vertical leg along the outer side of the lining, the upper longitudinal edge of said section of the lining being formed of a longitudinally extending row of refractory bricks closely adjacent the hori-

11

zontally extending leg of the support next above said one support, at least one of the longitudinal edges of a section having a longitudinal projection inwardly of said horizontal member of the supports and extending in a general vertical direction a distance to overlap said horizontal member and the adjacent longitudinal edge of an adjoining section, and a plurality of spaced pins secured to said vertically extending leg and projecting downwardly into the lining.
